SLACK-LOOP WASHING MACHINE AND METHOD

Application filed August 14, 1926. Serial No. 129,241.

This invention relates to a washing machine for strands of textile goods used in the wet finishing process and to a method of treating the goods.

5 The principal objects of the invention are to provide a washing machine and process for the above mentioned general purpose in which the loops of the material are kept in slack condition all the way through the machine, thus providing an extremely long contact of the goods with the liquor and increasing the time required for any particular part of the goods to stay in the liquor, thus more thoroughly soaking it and taking up liquor 10 to a greater extent than would be the case if the goods were under tension; also to provide for the use of a comparatively weaker solution, thus reducing the cost of operation and having an improved effect upon the 15 cloth; to provide a machine in which the goods are in constant motion all the way through the machine; to provide means for taking the dirty water out of the main rolls and carrying it off from the machine so as 20 to prevent the contamination of the goods thereby; to provide for directing a spray of water against each string of goods as it is moving up in the machine toward the nip of the main rolls for more effectively cleansing 25 and rinsing; to provide a machine in which every yard of material is subjected to the same kind of treatment and for the same length of time, thus securing a uniform product; and to provide a folding device adapted 30 to act on the goods uniformly so that every yard is treated alike as stated above and so that no bunches of cloth are gathered together where the goods are compressed and there will be no thin or open spaces of the 35 goods as they pass through the liquor.

40 The invention also involves many other features particularly the gentle action of the machine on the goods due to the fact that the goods are not under strain or tension at any time during their passage through the machine. The rolls usually employed and turned by friction of the goods are entirely eliminated. The shrinkage of the goods has no effect on the action and cannot increase 45 the tension because there is none. The only

weight which the goods are required to lift is their own weight and the weight of the water carried by them.

An inside J-box is provided to give a few yards of slack between the nipping of the main rolls and the wringer rolls, thus avoiding tension at this point. 55

The system is adaptable for use with the very lightest of voiles, scrims, laces, etc. as well as the more substantial cloths. 60

In cases where the amount of water used is an important item this system presents an advantage in that the amount used is only 15 to 20% of that heretofore required. Consequently the only water which need be added as the process goes on is the amount equal to that squeezed out by the main rolls plus that required for filling the tub once or twice a day. 65

The problem of threading a continuous 70 spiral slack loop machine heretofore has practically excluded this type of machine. This machine involves three elements or features which do away with this kind of trouble.

75 1. The plating of the goods down uniformly in the back of the tub so that they slide down the curved wall toward the front of the machine in uniform orderly folds, each string in its own path so that tangling is avoided.

80 2. The bottom of the tub is so curved as to allow the strands to feed down gently by gravity thus preventing tangles and similar mechanical troubles. 85

3. The means for folding the cloth is placed at exactly the proper point with relation to the curve of the tub.

80 The wringer or squeeze rolls are attached directly to the delivery end of the tub, thus avoiding a separate machine and a separate drive at added expense. The wringer is also driven from the main part of the washer itself so that it necessarily operates in synchronism with the washer, thus eliminating the pulleys, clutches, etc. and preventing tension. An apron is provided under the wringer to save the liquor squeezed out. 95

100 It will be obvious that by eliminating the tension on the goods, the power required to

run the machine is very much less than in the tension types of washers. Three or four machines can be run by one operator, thus reducing the labor cost. The first cost of the machine is reduced.

5 The product of the machine is much softer and of a higher grade than that from the machines heretofore on the market. This is due to the fact that the machine has a uniform gentle action on the goods without stretch, stress or strain. Consequently the filling is not pulled out of place, figures are not distorted and tender stripes of such materials as artificial silk are not damaged. The 10 fabric turned out is with a very fine pliable feel.

Other objects and advantages of the invention will appear hereinafter.

Reference is to be had to the accompanying drawings in which

20 Fig. 1 is a side view of a wet finishing plant with the side wall of one of the washers removed to show a preferred embodiment of this invention; and

25 Fig. 2 is a plan of the same somewhat diagrammatic in form with some parts omitted.

The operation of the washing machine 9 is similar to that of many machines on the market with the exceptions which have been noted 30 above. The material comes in from the kier as indicated in the extreme right hand in Fig. 1 in a single strand and passes over the first roll 10 into the main rolls 11 driven by a motor 8. This strand passes down into the 35 bowl and collects in the bottom in the form of folds 7 which slide down the gently curved bottom to the lowest part thereof. Then it is drawn up again over the front roll 10 and between the squeeze rolls 11 at a point at the 40 side of the first strand. It then goes around a folding roll 16 and through this process several times as is indicated in the plan. It finally comes over to the front side of the washer after passing several times through 45 the liquor and back to the squeeze rolls and through them where it projects upwardly. All this time it is loose and free and never under tension.

50 The liquor is squeezed out of the several strands and collected in a suds box 12. This is full of impurities and is run off through an outlet 13 to a point outside the machine or into the sewer. This liquor therefore is not again mixed with the liquor in the bottom 55 of the bowl, but is discharged and has no further contaminating effect on the goods.

As the goods come up the substantially vertical line to the top roll 10 in a series of strands across the washer, they are subjected 60 to jets of fresh water from a water manifold 14 through a nozzle 15 opposite each string of goods. This assists materially in cleansing and rinsing. These nozzles are located directly above the level of liquor in the bowl 65 for this purpose.

The several strands go from the main rolls up over the three bar folding cleat roll 16 which rotates constantly and has three bars projecting at equal distances apart and extending across the tub. This roll folds each 70 strand back and forth against the slanting back of the tub, and the last strand goes from it into an inside J-box 17. This box provides a few yards of slack between the nip of the main rolls 11 and the wringer rolls 20 so that the goods are not under tension in passing from one to the other, even in case of shrinkage. This is a principle that is adopted throughout and it will be seen that the goods cannot be put under tension at any 75 point. It is to be observed that the folding cleat roll 16 is placed in such relation to the curve of the tub as to secure the best results. This relationship has been worked out experimentally and secures the best operating 80 conditions as shown. The shape of the gentle curve of the back and bottom of the tub is a very important factor to enable the several strands of material to go through their regular course without tangling and similar mechanical troubles. This also has been worked 85 out experimentally and particular attention is drawn to the fact that while the bottom of the tub at the front is shown as being drawn on the arc of a circle, it widens out above under the level of the liquor to form a slanting but gently curved surface to let the folds down gently to the bottom by gravity. In this way the several strands slide down the curve toward the front of the machine in uniform 90 orderly folds, each strand in its own path, without doubling forward or side-ways and thus preventing tangling.

95 The wringer (or squeeze rolls) 20 is shown as attached directly to the delivery end of the washer. This is an improvement over the standard practice of having it arranged as an entirely separate machine with a separate drive. In the present case the drive is directly from the washer itself through 100 sprocket-chains 29 so that it operates absolutely in synchronism with the main rolls. This eliminates expanding pulleys, slip 105 clutches, etc. and prevents any tension due to one machine working faster or slower than the other. It also reduces the expense of installation, both first cost and operating expenses. At the bottom of the wringer is an apron 30 for directing the liquor back into 110 the tub and saving it.

115 The plant is shown as involving the usual reel machine 21 and oxidizing machine 22 and then as going through a second washer 23, reel machine 24 and a final washer 25. These washers are all made alike and the description given one of them applies to all.

120 It will be seen that all the above advantages are secured in connection with the washers 9, 23 and 25 and that the whole plant is rendered more efficient at each point where 130

washing is done. The various advantages of the invention having been described in the preamble, they will not be repeated here.

Although I have illustrated and described only a single form of the invention I am aware of the fact that modifications can be made therein by any person skilled in the art without departing from the scope of the invention as expressed in the claims. Therefore, I do not wish to be limited to all the details of construction herein shown and described, but what I do claim is:—

1. In a wet finishing machine, the combination with means for preparing the goods and 15 a washing bowl, of a pair of main rolls in the bowl, adapted to receive a strand of goods therebetween, the bowl having a slanting rear surface having a gentle curve extending 20 toward the front for receiving the strand after it leaves the rolls, a front roll near the front of the machine to which the strand passes upwardly and then directly through the main rolls, a folding cleat roll above the main rolls but to one side, for receiving each 25 strand and folding it against the curved back of the bowl, an inside J-box in position for receiving the advance strand from the cleat roll in a folded condition in the same vertical plane as the other strands, and 30 squeeze rolls mounted on the bowl for receiving the strand from the J-box and delivering it, whereby the goods are kept in a loose untensioned condition throughout the washing operation.

2. The combination with a washing tub, of 35 a pair of main rolls, adapted to receive a strand of goods therebetween, the tub having a slanting rear surface having a gentle curve extending toward the front for receiving one strand indirectly from the rolls, said strand extending upwardly near the front of the machine, a front roll for receiving the strand and directing it again through the main rolls at a different point, and a folding cleat roll, to one side, above the main roll and at the rear for receiving the strands therefrom and so located as to drop the strands in a folded condition on the slanting rear surface of the tub, said strands passing in the same way through the main rolls, folding roll, and liquor several times and having a separate path at all times for the different strands.

3. The process of wet finishing textile materials which consists in leading a continuous strand of the goods between a pair of main rolls and repeatedly passing the same strand in a general helical direction between the main rolls, leaving them loose at all points on both sides of the main rolls and then leading them to a wringing device and keeping the goods in a slack condition between the main rolls and the wringing device.

4. The process of wet finishing textile materials which consists in leading a continuous strand of the goods between a pair of main

rolls, repeatedly passing the same strand in a general helical direction between the main rolls, then leading them to a wringing device, keeping the goods in a slack condition between the main rolls and the wringing device, and rinsing each strand of the goods as they pass upwardly to the main rolls during the washing operation.

5. The process of wet finishing textile materials which consists in leading a continuous strand of the goods between a pair of main rolls, repeatedly passing the same strand in a general helical direction between the main rolls, leaving them loose at all points on both sides of the main rolls, then wringing them and keeping the goods in a slack condition between the main rolls and the wringing device.

6. In a wet finishing machine, the combination with a washing tub or bowl, of a pair of main rolls adapted to receive a strand of goods therebetween, a front roll for directing the strand thereto, and guiding it up at the front of the machine, and directing it again through the main rolls, said goods passing in the same way through the liquor and main rolls several times and having a separate path at all times for the different strands, a J-box for receiving the advance strand in a folded condition, a wringer mounted on the tub for receiving the strand from the J-box and delivering it from the tub.

7. In a wet finishing machine, the combination with a washing tub or bowl, of a pair of main rolls adapted to receive a strand of goods therebetween, a front roll over which the strand passes, and guiding it up at the front of the machine, and directing it again through the main rolls, said goods passing in the same way through the liquor and main rolls several times and having a separate path at all times for the different strands, a J-box for receiving the advance strand in a folded condition, a wringer mounted on the tub for receiving the strand from the J-box and delivering it from the tub, and means for driving the wringer in synchronism with the main rolls.

8. In a washing machine, the combination with a tub, of a pair of main rolls adapted to receive a strand of goods therebetween, a folding cleat roll above the main rolls and to one side for receiving the strands and folding them against the back of the bowl, the tub having a slanting rear surface having a gentle curve extending toward the front for receiving the strand from the cleat roll, a front roll for receiving the strand upwardly from the liquor in the tub and directing it again through the main rolls at different points therealong, said strands passing in the same way through the main rolls several times, an inside J-box for receiving the advance strand from the cleat roll in a folded condition, and squeeze rolls mounted on the tub for receiv-

ing the strand from the J-box and delivering it from the tub, whereby the goods are kept in a loose untensioned condition throughout the washing operation, and means for driving the squeeze rolls in synchronism with the main rolls.

9. In a wet washing machine, the combination with a tub, of a pair of main rolls adapted to receive a strand of goods therebetween, means for receiving the strand therefrom and directing it to the bottom of the tub, a front roll for receiving the strand from the bottom of the tub and directing it again through the main rolls, said strand passing in the same way in laps through the main rolls several times, and means for spraying fresh water against the several laps as they move upwardly in the tub at a point between the surface of the liquor in the tub and the front roll for rinsing the goods, an inside J-box for receiving the advance lap in a folded condition, and means separate from said main rolls for receiving said lap from the J-box and wringing the same.

10. In a wet washing machine, the combination with a tub, of a pair of main rolls adapted to receive a strand of goods therebetween and feed the strand along, means to repeatedly pass the same strand in a general helical direction between the main rolls, leaving it loose at all points on both sides of the main rolls, and a wringing device in position for receiving and keeping the goods in a slack condition between the main rolls and the wringing device.

11. In a wet washing machine, the combination with a tub, of a pair of main rolls adapted to receive a strand of goods therebetween and feed the strand along, means to repeatedly pass the same strand in a general helical direction between the main rolls leaving it loose at all points on both sides of the main rolls, and an inside J-box for receiving an advance strand of the goods from the main rolls and adapted to deliver said strand to the wringer.

12. In a wet washing machine, the combination with a tub, of a pair of main rolls adapted to receive a strand of goods therebetween and feed the strand along, means to repeatedly pass the same strand in a general helical direction between the main rolls, leaving it loose at all points on both sides of the main rolls, a wringing device, and means for rinsing each strand of the goods as it passes upwardly to the main rolls during the washing operation.

In testimony whereof I have hereunto affixed my signature.

60 HOMER C. RIGGS.
